(57) **CLAIM**

I claim the ornamental design for an animal puzzle, as shown.

DESCRIPTION

FIG. 1 is a top plan view of the animal puzzle showing my new design, a bottom plan view thereof being flat and unornamented;

FIG. 2 is a right side elevation view thereof, a left side elevation view being identical; and,

FIG. 3 is a front elevation view thereof, a rear elevation view being identical.

The broken lines in the drawings are for illustrative purposes only and do not form part of the claimed design.
